UNITED STATES PATENT OFFICE.

GURDON W. HULL, OF WALLINGFORD, CONNECTICUT.

DESIGN FOR A CASTANET.

SPECIFICATION forming part of Design No. 21,953, dated November 1, 1892.

Application filed August 23, 1892. Serial No. 443,911. Term of patent 7 years.

To all whom it may concern:

Be it known that I, GURDON W. HULL, a citizen of the United States, residing at Wallingford, in the county of New Haven and State of Connecticut, have invented and produced a new and original Design for Castanets, of which the following is a specification, reference being had to the accompanying drawings, forming part thereof.

10 Figure 1 is a front view of a castanet, showing my design. Fig. 2 is a rear view of the castanet, showing the design.

The leading feature of my design consists in the raised ornamented surface forming the 15 central part of the castanet, the surface being corrugated lengthwise, consisting of alternate grooves and raised surfaces running from the base to the front, widening out toward the center, and again narrowing toward 20 each other at the front edge, the raised surfaces terminating in a scallop at this point and presenting a species of scalloped surface around the edge of the central part.

A denotes the body part of the castanet, which is circular, or substantially so, in general 25 outline and is provided with a narrowed portion b, forming what may be termed a "neck." The castanet is composed of two parts c and d, secured together and arranged so as to overlap each other, the central portion of each part 30 being raised or dome shaped above the same, and the outer portion conforming in general outline to the shape of the central raised portion.

It is the ornamentation of the body part 35 and sounding-chambers that forms the essential and leading feature of my design.

What I claim as my invention is—

The design for a castanet, substantially as shown in the accompanying drawings, and 40 substantially as described in the accompanying specification.

GURDON W. HULL.
